United States Patent Office

Des. 198,364
Patented June 9, 1964

198,364

RESTAURANT

Fred S. Toguchi, Cleveland, Ohio, assignor to Royal Castle, Inc., Cleveland, Ohio, a corporation of Ohio

Filed Aug. 29, 1963, Ser. No. 76,396

Term of patent 14 years

(Cl. D13—1)

FIG. 1

FIG. 2

FIG. 3

FIG. 4

FIG. 5

FIG. 1 is an elevational view taken from the bottom of FIG. 3, showing my new design;

FIG. 2 is an elevational view taken 112½ degrees counter clockwise from FIG. 1 on FIG. 3;

FIG. 3 is a plan view;

FIG. 4 is a section taken on line 4—4 of FIG. 3; and FIG. 5 is a section taken on line 5—5 of FIG. 3.

The essential features of my design are shown in the solid lines.

I claim:

The ornamental design for a restaurant, as shown and described.
